UNITED STATES PATENT OFFICE

155,362

DESIGN FOR AN AIRPLANE

Calvin Thomas Ray, Baltimore County, Md., assignor to The Glenn L. Martin Company, Baltimore, Md.

Application October 28, 1947, Serial No. 142,177

Term of patent 14 years

(Cl. D71—1)

To all whom it may concern:

Be it known that I, Calvin Thomas Ray, a citizen of the United States and resident of county of Baltimore, State of Maryland, have invented a new, original, and ornamental Design for an Airplane, of which the following is a specification, reference being had to the accompanying drawings, forming a part thereof.

Figure 1 is a fragmentary perspective view of a portion of an airplane fuselage, broken away to show the hostess station in the interior thereof.

Figure 2 is a fragmentary perspective view of the corresponding portion of the airplane, looking in the generally opposite direction from Figure 1.

Figure 3 is a fragmentary sectional view through the airplane fuselage showing in plan the hostess station.

Figure 4 is a fragmentary sectional view

through the airplane fuselage showing in elevation the hostess station.

Figure 5 is a plan view of the complete airplane.

The characteristic features of my design reside in those portions, especially of the interior, shown by means of full lines in the drawing.

I claim:

The ornamental design for an airplane, substantially as shown and described.

CALVIN THOMAS RAY.
